UNITED STATES PATENT OFFICE.

PETER MIGLIO, OF MARSEILLES, ILLINOIS.

MINER'S LAMP.

Application filed March 29, 1922. Serial No. 547,760.

To all whom it may concern:

Be it known that I, PETER MIGLIO, a citizen of the United States, residing at Marseilles, in the county of La Salle and State 5 of Illinois, have invented certain new and useful Improvements in Miners' Lamps, of which the following is a specification, reference being had to the accompanying drawings.

10 This invention relates to miners' lamps, and particularly to miners' lamps using acetylene gas.

In miners' lamps as ordinarily constructed, there is but one burner and as a consequence if this burner becomes clogged or blocked so that a jet of gas cannot issue therefrom, the miner is obliged to stop work and clean out the opening of the burner, thus losing time. Furthermore, in miners' acetylene lamps it is usual to connect the body of the lamp to the water reservoir and gas generator by means of screw-threads. The carbide causes a sort of cement to form between these screw-threads and as a consequence the lower portion of the lamp cannot be unscrewed from the upper portion and the lamp must be thrown away or the lower portion of the lamp broken off in attempting to unscrew and detach the water reservoir and generator. Furthermore, in the ordinary miners' lamps of this character there is a cap clasp which is mounted upon the lamp itself and which forms an encumbrance.

35 One of the objects of the present invention is to provide a lamp of this character with two burners and a valve shiftable to close one of the burners and permit the passage of the gas through the other burner, 40 or close off the last named burner and permit the passage of the gas through the first named burner so that if one of the burners become clogged it is only necessary for the valve to be shifted and the diminishing flame 45 from the clogged burner will light the jet issuing from the burner which is open, thus permitting the miner to clean out the clogged burner at his leisure.

A further object is to provide very simple means whereby this opening and closing of the two burners may be accomplished.

A still further object is to provide for a detachable connection between the base or gas generating portion of the lamp and the body of the lamp which does not require screw-threads and which thus permits the

body and generator to be readily detached from each other when necessary, this connection being such, however, that the generator and the body will be held in gas-tight engagement with each other.

Still another object is to provide a clasp adapted to be permanently attached to the cap of the miner and which is adapted to engage the base of the hook usually found on lamps of this character, thus rendering the lamp free of the encumbrance of the clasp and thus permitting it to be handled more readily.

Other objects will appear in the course 70 of the following description.

My invention is illustrated in the accompanying drawings, wherein:

Figure 1 is a side elevation of a miner's lamp constructed in accordance with my 75 invention;

Figure 2 is a vertical sectional view thereof;

Figure 3 is a top plan view of the construction shown in Figure 1;

Figure 4 is a horizontal section on the line 4—4 of Figure 1.

Referring to these drawings, 10 designates the base or carbide-containing chamber and 11 the body of the lamp, which is designed to fit over this chamber and have gas-tight engagement therewith, as usual. The body 11 has the usual form and is closed at its upper end by a plate 12 having the usual filling opening closed by a cap 90 13. The front of the body carries upon it a reflector 14 of the usual type but projecting through this reflector adjacent the center thereof are two gas discharging tubes 15 and 16, each having proper burners at 95 their outer ends. These tubes, as illustrated in Figure 2, extend inward through the wall of the body 11, then extend downward, and then inward or toward each other, as at 17, these inner ends of the tubes 100 being open.

Disposed between the confronting ends 17 of the tubes 15 and 16 is a sleeve 18 which encloses a solid rubber block 19 constituting a valve. When this sleeve 18 is shifted in one direction, the rubber block will bear against one of the ends 17 and close this particular gas tube, while when it is shifted in the other direction it will close the other gas tube. The amount of this movement 110 necessary in order to close one or the other gas tubes is very slight. The sleeve 18 has

a laterally projecting portion 20 which is interiorly screw-threaded, and engaging this interior screw-thread is a wire or rod 21 which extends out through a tube 22 which is attached to the wall of the body 11 and projects in both directions from this wall. Within this tube is disposed a rubber sleeve 23 which fits around the wire or rod 21 tightly so as to prevent the escape of 10 gas, this sleeve forming a packing.

Fitting over the outer projecting end of the tube 22 is a cap 24 which is longitudinally movable upon the tube 22 and which has an interior rubber lining or sleeve 25 fitting the tube closely. The rod or wire 21 is attached at its end to this cap 24 so that when the cap moves longitudinally the wire or rod will move longitudinally and vice versa. The extremity of the cap has an internally screw-threaded socket with which a screw 26 is adapted to engage, and attached to this cap 24 by the screw 26 is an outwardly projecting arm 27, the extremity of which is perforated. Projecting from the side wall 25 of the body 11 and attached firmly thereto is an interiorly screw-threaded, tubular member 28, and having screw-threaded engagement with this member is the rod 29. The extremity of this rod passes through the 30 perforation in the extremity of the arm 27 and is provided with shoulders 30 on each side of the arm 27.

It will be obvious now that by rotating the rod 29 in one direction or the other, the 35 screw-threads on the sleeve 28 will cause the rod 29 to move longitudinally and this longitudinal movement will be transmitted by the arm 27 to the cap 25 and thus to the rod 21, which by reason of its connection to the 40 sleeve 24 causes the valve constituted by this sleeve and the plug 19 to shift longitudinally into engagement with one or the other of the branches 17 of the gas pipes 15 or 16. Normally, of course, this valve is held 45 against one of the branches 17 so as to permit the free entrance of gas into the other branch and its exhaust through the appropriate gas pipe or tip. If this tip of the gas pipe becomes clogged so that the light is reduced or is failing, then the handle on the 50 rod 29 is turned and this causes the movement of the valve 20 in the manner heretofore described so as to close this clogged pipe to the entrance of gas and permit the 55 entrance of gas into the unclogged pipe. It will, of course, be understood that the branches 17 of the pipe 16 open beneath the septum 31 which forms the bottom of the water chamber 32. Extending downward 60 from the water chamber is the usual water supply pipe 33 which discharges into the carbide receptacle 10 and the discharge of water is controlled by the usual valve, the valve rod of which is designated 34. Inasmuch as this valve and valve rod are com-

monly found on all acetylene lamps of this character, it is not believed necessary to particularly describe it.

The lower end of the body 11 is outwardly flared, as at 35, and the upper end of the carbide receptacle 10 is formed with a neck 36 and immediately around the neck with a seat 37 for a gasket 38, against which the flared lower end of the body 11 bears. For the purpose of securely holding the body 11 to the carbide receptacle and generator 10, I form the upper end of the portion 10 with an interrupted flange 39, this flange being interrupted at a plurality of points, as at 40. The flange adjacent each interruption 80 is bevelled, as at 41. The body has attached to it a plurality of downwardly extending hooks 42 which extend downward and outward and then sharply inward, and when the body and generator are put together 85 these hooks pass down through the interruptions 40 and then the body of the lamp is given a turn in one direction and the hooks move along the bevelled face 41 and draw the body 11 into close and gas-tight engagement with the carbide receptacle or generator 10. This construction avoids the necessity of using screw-threads and provides a construction whereby the two sections of the lamp may be readily separated from each 90 other and readily and quickly joined and avoids the objections before referred to incident to screw-threading the two sections together.

The body portion 11 is provided with the usual hook 43 whereby the lamp may be connected to the miner's cap. This hook is made somewhat longer than the usual hook and extends downward and across the circumferential recess 44 in the body 11. A clip 45 formed of a strip of resilient metal is intended to be attached to the miner's cap, this strip at its middle being folded or corrugated, as at 46, to provide a resilient socket 47 between the corrugations which is adapted 110 to embrace that portion of the hook 43 which extends across the recess 44.

The advantages of my invention reside in the fact that by having two burners, when one burner is blocked the miner can turn it 115 off and turn the other on and so have a light immediately; thus losing no time in looking for a light while attempting to drill out the blocked burner. The other burner can be drilled at his leisure. When a burner is 120 blocked, it is seldom completely blocked so that a little light still shows and thus when the other burner is turned on it lights without the use of a match. The valve, it will be seen, is made in three pieces so that any one 125 of them can be removed and replaced in case of necessity. The advantage of the clasp 45 is that the clasp is always on the miner's cap and does not make the lamp ungainly and hard to handle, as it would do if the clasp 130

were on the lamp. At the same time it embraces the hook strongly and holds the lamp firmly in place against accidental detachment or swinging. By disposing the valve 5 between the two branches 17, it is obvious that the valve in shifting from a position closing one gas pipe to a position closing the other gas pipe will traverse a point where both pipes are open so that the gas is 10 passing to the clogged pipe and to the free pipe at the same time so that the gas issuing from the free pipe can become ignited from the small amount of gas issuing from the clogged pipe.

15 While I have illustrated certain details of construction which I have found to be particularly effective, it is obvious that these details might be changed in many ways without departing from the spirit of the invention, and it will be obvious that various attachments ordinarily found in miners' lamps may be used with a lamp constructed in accordance with the present invention, but that I have shown only so much of a 20 miner's lamp as relates to my specific invention.

I claim:—

1. In an acetylene lamp of the character described, a body constituting a water 30 chamber and a carbide chamber connected to the body but separated from the water containing chamber, a pair of burner pipes extending through the side wall of the body and opening into the carbide chamber, said 35 pipes having confronting inner ends, a valve disposed between the confronting ends of the burner pipes and shiftable into contact with one or the other of the burner pipes, and means exterior to the body whereby the 40 valve may be shifted.

2. In an acetylene lamp of the character described, a body constituting a water chamber and a carbide chamber connected to the body but separated from the water 45 containing chamber, a pair of burner pipes extending through the side wall of the body and opening into the carbide chamber, said 50 pipes having confronting inner ends, a valve disposed between the confronting ends of the burner pipes and shiftable into contact with one or the other of the burner pipes, a rod attached to the valve and extending out through the side wall of the body, a 55 packing sleeve through which the rod passes, and means for longitudinally shifting the rod.

3. In an acetylene lamp of the character described, a body constituting a water chamber and a carbide chamber connected 60 to the body but separated from the water containing chamber, a pair of burner pipes extending through the side wall of the body and opening into the carbide chamber, said

65 pipes having confronting inner ends, a valve disposed between the confronting ends of the burner pipes and shiftable into contact with one or the other of the burner pipes, a rod attached to the valve and extending out through the side wall of the body, a 70 second rod having screw-threaded engagement with the body, and an arm carried by the second rod for rectilinear movement with it and operatively connected to the valve rod.

4. In an acetylene gas lamp, a body having a water containing chamber, a carbide chamber adapted to be operatively connected to the body, a pair of burner pipes extending through the side wall of the body and downward into the upper end of the 80 carbide chamber, the inner ends of the pipes confronting each other, a valve disposed between the inner ends of the pipes and longitudinally shiftable to close one or the other pipe, a rod attached to the valve and 85 extending out through the side wall of the body, a metallic sleeve through which the rod passes, packing in said sleeve through which the rod passes, a longitudinally movable cap engaging over the outer end of the 90 sleeve and having sliding movement thereon and attached to said rod, an adjusting rod having screw-threaded engagement with the body to cause a rectilinear movement of the rod when the rod is rotated, and an 95 arm operatively connected to said adjusting rod and operatively connected to the cap whereby to cause the simultaneous shifting of the valve rod and of the adjusting rod.

100 5. In an acetylene gas burner, a body having a water chamber, a carbide chamber engaging the body, a pair of burner pipes extending through the side wall of the body and opening into the upper end of the carbide chamber and having confronting inner extremities, a valve disposed between the confronting ends of the burner pipes and comprising a sleeve and an elastic block disposed within the sleeve and carried 105 thereby, the sleeve having an interiorly screw-threaded projecting portion, a valve rod having screw-threaded engagement with the projecting portion of the sleeve and extending out through the side wall of the 110 body, a metallic sleeve attached to the side wall and through which the rod passes, a packing lining within said sleeve, a cap fitting over the outer end of said sleeve and having longitudinal movement with relation 115 thereto, and manually operable means for longitudinally shifting said cap and holding it in its adjusted position.

In testimony whereof I hereunto affix my signature.

PETER MIGLIO.
